(57) **CLAIM**

The ornamental design for a golf green reading tool, as shown and described.

DESCRIPTION

FIG. 1 illustrates a first front perspective overview of a golf green reading tool;

FIG. 2 illustrates a second front perspective overview thereof;

FIG. 3 illustrates a first rear perspective overview thereof;

FIG. 4 illustrates a second rear perspective overview thereof;

FIG. 5 illustrates a perspective overview thereof;

FIG. 6 is a front view thereof;

FIG. 7 is a top view thereof;

FIG. 8 is a side view thereof;

FIG. 9 is a bottom view thereof, and,

FIG. 10 illustrates an elevated top view thereof.

The broken lines in FIGS. 5 and 10 depict environment and form no part of the claimed design.
